United States Patent Office

Des. 220,610
Patented May 4, 1971

220,610

JUG

David G. Hills, Collinsville, Conn., assignor to Monsanto Company, St. Louis, Mo.

Filed Dec. 30, 1968, Ser. No. 15,137

Term of patent 14 years

Int. Cl. D9—01

U.S. Cl. D9—48

FIG. III

FIG. I

FIG. II

FIG. I is an elevational view of a jug showing my new design, the opposite side being a mirror image of the side shown;

FIG. II is an elevational view looking from the right of FIG. I; and

FIG. III is a top plan view thereof.

I claim:

The ornamental design for a jug, as shown and described.
